UNITED STATES PATENT OFFICE

2,462,068

VIBRATORY POLISHER

Richard R. Butts, Miamisburg, Ohio

Application August 13, 1946, Serial No. 690,141

7 Claims. (Cl. 172—126)

1

The present invention relates to an electrical appliance for rubbing, polishing, sanding and abrading operations and has for an object the provision of a simple, sturdy and effective electromagnetically operated device.

Another object of the invention is to provide a device wherein the housing or casing forms a convenient unit to be gripped in the hand of the user and through which the plug of an electric supply cord may be passed.

Still another object of the invention is to provide an electromagnetic device for polishing, buffing, and similar operations wherein a vibratory armature protectively concealed within the casing is provided with an antifriction bearing on the core of the electromagnet whereby the armature is energized, thereby enabling the user of the device to exert appreciable pressure in polishing, buffing and abrading operations.

A further object of the invention is to provide a device of this kind which is adapted for the removable mounting of selected work plates provided with various working webs or sheets.

These and other objects are attained by the means described herein and disclosed in the accompanying drawings, in which:

Fig. 1 is a top plan view of a device embodying the invention.

Fig. 2 is a side elevational view of the device of Fig. 1 with the operating mechanism shown in dotted lines.

Fig. 3 is a front end elevational view of the device with the casing largely broken away.

Fig. 4 is a top plan view of the mechanism of the device, the casing being removed.

Fig. 5 is a side elevational view of the mechanism shown in Fig. 4.

Fig. 6 is a rear end elevational view of the device of Fig. 4.

Fig. 7 is a cross-sectional view taken on line 7—7 of Fig. 5.

Fig. 8 is a cross-sectional view taken on line 8—8 of Fig. 4.

Fig. 9 is a cross-sectional view taken on line 9—9 of Fig. 5.

Fig. 10 is a cross-sectional view taken on line 10—10 of Fig. 2.

Various field operations in the nature of buffing, polishing and rubbing such as in the cleaning and polishing of automobiles, for examples, have been largely carried on by hand at the expense of much manual labor. One or more well-known types of automobile polish particularly require hard rubbing in order to attain the de-

2

sired finish on the protective coating which they form.

By the means of the present invention an easily manipulable device is provided wherein the polishing, rubbing or buffing operations are effected through the agency of an electromagnetically vibrated armature, to the end of which is removably applied a plate of sufficient working area on which the polishing or other web is carried.

Reference is now made to the drawings wherein in a light-weight, rigid casing 15, which may be made of formed sheet metal, or a light-weight molded or cast body, has an entire open bottom 16 through which the operating mechanism, indicated generally at 17, is entered. The top of the casing is preferably provided with a dished concavity or depression 18 through which one of the mounting screws 19 is passed leaving the head of the screw counter-flush with the normal top of the casing. The casing 15 is narrow at the top and rounded toward the rear as a handle, while the lower side and front portions are outwardly flared to form a protective skirt which conceals the lower part of the operating mechanism. An E-shaped electromagnet core 21 is rigidly mounted on the interior wall of casing 15 at the top by a shouldered bracket 22, the depending parallel arms 23 of which embrace the top or upper leg 24 of the electromagnet and are secured thereto by means of rivets 25. Bracket 22 has inwardly extending shoulders 26 which lie in spaced relation with the top face of the upper leg 24 of the magnet core and the outer corners of these shoulders are deformed as at 27 intermediate the edges of the bracket to form lugs which seat in complementary notches 28 in arm 29 of a generally L-shaped spring 30. The remaining arm 31 of spring 30 is welded to the upper end 40 of an armature 32 which is normally held by said spring in slightly spaced relation to the ends of the legs of the E-shaped electromagnet core 21. The free end of armature 32 is turned at right angles to the armature to form a bearing plate 33 having a longitudinal slot 34 for seating a bearing ball 35. It will be noted that bearing plate 33 is in spaced parallel relation to the bottom face of the lower leg 36 of the core 21. A U-shaped bracket 37 embraces the lower face and sides of leg 36 and it is fastened thereto by any suitable means such as rivets 38. A slot 39 in bearing bracket 37 is normally in registry with the slot 34 in bearing plate 33. Said bracket and plate are slightly spaced and the ball 35 interposed between the plates serves as a reciproca-

tory bearing for relative movement of the parts as the armature 32 is vibrated in known manner when the electromagnet is energized. An electromagnet coil 40 is carried on the intermediate leg 41 of core 21. An insulating plug member 42 is secured to the rear edge of core 21 by a bracket 43 riveted to the core at its sides and apertured in the rear to allow insulating member 42 to protrude. Terminals 44 and 45 are suitably secured in the insulating member 42 and have the terminal ends 46 and 47 of the coil 40 electrically connected thereto. A suitable electric socket member 48 has an electric supply cord 49, and the rear of casing 15 is apertured at 50 to permit removable entry of plug 48 to electrically connect the device with a suitable source of A. C. supply.

From the foregoing it will be appreciated that when the electromagnet is energized the vibration of armature 32 will permit of edgewise planar reciprocation of the bearing plate 33 with respect to the bottom of the armature. A U-shaped bracket 51, secured to and projecting horizontally from the lower end of the core, is adapted to receive a screw 52 passing through the exterior of the casing whereby the core is rigidly held against end thrust due to vibration of the armature. A clip plate 53 has three upwardly struck lugs 54 which serve to positively locate bearing plate 33 thereon and any suitable means such as spot welds 55 serve to fix these parts together permanently. Clip plate 53 is preferably squared and the bearing plate is perfectly centered therewith and with the ball and slot bearing.

Removably and interchangeably connectable to the bottom face of clip plate 53 is a working plate 56 covered on its bottom and around the edges thereof with a working web or sheet 57 of polishing or abrading material. Four lugs 58 are struck upwardly from the body of working plate 56, these lugs being disposed in opposed pairs spaced apart to receive plate 53 snugly between them intermediate the several corners. Each lug 58 has an inwardly projecting boss 59 located sufficiently above the top face of working plate 53 between the lugs and holding the parts firmly together under the limited resiliency of the lugs. The working plates are relatively inexpensive items to make and a plurality of such plates individually covered with polishing or buffing material or with abrading material of various grades may be provided in order to quickly convert the device to use in a series of rubbing operations. The working web 57 may be cemented or otherwise firmly fixed to the plate by any suitable means (not detailed).

The operation of the device will be readily understood to be adaptable to a variety of uses. The numerous operations in automobile body and fender repair work may be speeded up and simplified by the use of the device in abrasively removing rust, shaping repair patches, rubbing down priming and finishing coats and in polishing and cleaning the body finish and accessories in general. In all of these and other operations, regardless of whether a light or a heavy manual pressure is to be applied, the bowed or rounded angle portion 39 of the armature mounting spring permits the armature 32 to vibrate under the influence of the electromagnet, while the manual pressure imposed on the casing and through it ultimately to the working web is taken up on the small antifriction bearing afforded by the ball working on the edges of the slots. The thrust of the manual pressure is thus always substantially

centered on the plate during reciprocation thereof.

What is claimed is:

1. In a device of the class described the combination of an open bottomed casing, an electromagnet core rigidly mounted in upright position within the casing, an L-shaped armature assembly mounted for vibratory movement adjacent an upright edge of the core and having the free bottom end thereof turned under in spaced parallelism with the bottom edge of the core, a ball and slot bearing substantially limiting said end of said armature to reciprocation in parallelism with the bottom longitudinal edge of the core, a working plate detachably connected for reciprocation with said free end of said armature, and a working web fixed on the bottom face of said working plate.
2. In a device of the class described the combination with an E-shaped electromagnet, of a bearing fixed on the bottom edge thereof and provided with a short slot extending longitudinally of said bottom edge, the electromagnet comprising a vibratory armature operatively extending along the side edge and turned angularly in parallelism with the bottom edge beneath the bearing bracket, said turned under end of the armature being slotted in registry with the slot in the bearing bracket, a ball interposed in the slots and disposed for engagement with the edges of the respective slots, a web carrying working plate, and means detachably connecting said turned under end of the armature with said working plate.
3. In a device of the class described, an upright E-shaped electromagnet comprising spaced horizontal legs, a bearing bracket extending across the bottom face of the lower leg adjacent the free end thereof and provided with a short center slot extending longitudinally of said leg, an open bottomed casing protectively enclosing said electromagnet, means on the upper leg of the electromagnet whereby the electromagnet is rigidly fixed to the top interior of the casing, a substantially L-shaped spring fixed at one end to the electromagnet by said supporting means, an armature fixed to the opposite end of the spring for vibration adjacent the ends of the legs of said electromagnet, the free end of the armature being slotted similarly to the bearing bracket and turned angularly beneath and in spaced parallelism with said bracket, a bearing ball disposed between and seated in said slots, means supporting the lower end of the electromagnet on the interior of the casing, a pair of electrical terminals mounted in insulated relation interiorly of the casing, the casing having an aperture opposite said insulating member, a terminal-receiving socket for removable connection with the terminals through the aperture in the casing whereby the electromagnet is energized, and means for detachably mounting a web-carrying working plate on the free end of the armature and in parallelism with the bottom leg of the electromagnet.
4. In a device of the class described the combination of an electromagnet, a vibratory armature operable thereby and having a slotted end portion turned beneath it and in parallelism with the bottom of the electromagnet, an anti-friction ball operating in said slot and resisting movement of said turned end of said armature save in longitudinal parallelism with the bottom thereof, detachable means for energizing the electromagnet, an open bottomed casing fixedly

mounted over the electromagnet and exposing the turned end of the armature, means for securing the uppermost portion of the electromagnet to the top interior of said casing whereby said electromagnet is rigidly and vertically suspended in the casing, and a web-carrying working plate detachably connected with said turned end of the armature for reciprocation longitudinally beneath the open bottom of the casing.

5. An electromagnet polishing device comprising an electromagnet core, a casing surrounding the core save at the bottom thereof, a substantially vertical armature operatively associated with said core and having end portion extending through the casing and turned in substantial parallelism with the bottom of the core, a thrust bearing between the armature and the core constraining the end of the armature to substantially rectilinear movement, and a rigid working plate supported flatwise on said portion of said armature.

6. In a device of the class described an electromagnet including an armature having the free end turned beneath it, means comprising parallel shoulders formed by slots in the armature and core, and a captive bearing ball riding on said shoulders constraining the turned end of the armature to rectilinear planar movement parallel to the bottom of the core, a web-carrying, working plate mounted flatwise on the bottom of said turned end of the core, a protective casing serving as a handle for the electromagnet and ex-

posing the working plane exteriorly thereof, and means for energizing the electromagnet.

7. In a polishing device the combination of an open bottom casing, a vertical E-shaped electromagnet rigidly secured at its top to the top interior of the casing, the arms of the core of said electromagnet being disposed horizontally, one above the other, a bearing bracket fixed to the lowermost arm on the bottom thereof, a vertical armature yieldably supported in parallelism with the outer ends of all of said arms, means movable with the bottom end of the armature and disposed beneath and in parallelism with the said lowermost arm of the core, an antifriction bearing between said means and the bearing bracket for constraining said means to movement longitudinally and parallel only with the lowermost arm, a work plate carried by said means, and means for energizing the electromagnet.
